UNITED STATES PATENT OFFICE.

ELLEN EGBERTSON, OF BROOKLYN, NEW YORK.

PIE-DISH.

SPECIFICATION forming part of Letters Patent No. 429,513, dated June 3, 1890.

Application filed January 13, 1890. Serial No. 336,728. (No model.)

To all whom it may concern:

Be it known that I, ELLEN EGBERTSON, a citizen of the United States, residing at Brooklyn, in the county of Kings and State of New York, have invented certain new and useful Improvements in Pie-Dishes; and I do hereby declare the following to be a full, clear, and exact description of the invention, such as will enable others skilled in the art to which it

appertains to make and use the same.

This invention relates to pie-dishes; and it consists in the novel construction and combination of the parts hereinafter fully described and claimed.

In the drawings, Figure 1 is a plan view of the pie-dish from above; and Fig. 2 is a cross-section through the same, taken on the line $x x$ in Fig. 1.

The object of this invention is to provide a pie-dish which will be more handy to lift about than those heretofore in common use and to prevent the contents of the pie-dish from running over.

A is the pie-dish, provided with the outwardly and upwardly inclined portion a , and having a horizontal flange B surrounding the upper edge of said inclined portion, and provided with the strengthening-bead b .

C is a vertical ring provided with the strengthening-bead c around its top edge, and having its lower edge secured to the said horizontal flange B by solder c' .

D are the tongues of metal projecting from the lower edge of the ring C and resting upon the surface of the inclined portion a of the pie-dish. These tongues are soldered to the pie-dish, so that the vertical ring is very firmly attached to it, and the solder around the bottom edge of the ring makes a tight joint, so that the contents of the pie-dish cannot run out.

The pie-dish can be lifted about with great facility by means of the horizontal beaded flange B.

What I claim is—

The combination, with a pie-dish provided with the outwardly and upwardly inclined portion and the horizontal beaded flange around the top edge of said inclined portion, of a vertical ring provided with a bead around its top edge and tongues projecting inwardly below its bottom edge and resting upon the said inclined portion of the pie-dish, the said tongues and the bottom edge of the ring being firmly soldered to the pie-dish, so that the contents of the dish cannot leak out under the ring, substantially as and for the purpose set forth.

In testimony whereof I affix my signature in presence of two witnesses.

ELLEN EGBERTSON.
